UNITED STATES PATENT OFFICE.

FOREST F. AULT, OF WILMETTE, ILLINOIS, ASSIGNOR TO THE BORROWMITE COMPANY OF AMERICA, OF CHICAGO, ILLINOIS, A CORPORATION OF ILLINOIS.

MECHANISM AND PROCESS FOR EFFECTING REGENERATION.

Application filed February 16, 1921. Serial No. 445,415.

My invention relates to improvements in water softening apparatus and method, and has special reference to improvements in the automatic control of the flow of water and 5 brine in systems which make use of brine for regenerating the water softening filter bed.

As heretofore used and controlled the shutting down or stopping of the flow of the water and the brine has been gradual. The 10 flow both of the brine and the fresh water through the filter bed in less than a predetermined quantity is not sufficient for the reason that a small flow of the water does not spread out evenly throughout the filter 15 bed but takes a short course, or the one of least resistance, from the inlet to the outlet with the result that a large percentage of time, brine and slush water are lost so far as any practical or effectual result is concerned.

One important feature of my invention relates to the maintaining of a full flow of the liquid (brine and flush water) during the time that they are respectively flowing and the substantially instantaneous closure 25 of the control valves at the end of the predetermined time interval.

Furthermore I provide automatic means for controlling the time interval during which the flush water is flowing and which is 30 adjustable to attain the result desired.

For operating the valve I provide hydraulic means controlled by a simple trip mechanism whereby the main flush water valve is operated by hydraulic pressure and is substantially instantaneously operated at the 35 proper point in the operation of the system.

My invention will be more readily understood by reference to the accompanying drawings forming part of this specification, 40 and in which:

Figure 1 is a view partly in section and partly in elevation illustrating my improved apparatus which I have found best adapted for practicing my improved method;

Figure 2 is a top plan view of said apparatus;

Figure 3 is a fragmentary vertical section substantially on the line 3—3 of Figure 1;

Figure 4 is a fragmentary vertical section 50 similar to Figure 1 but looking in the opposite direction;

Figure 5 is a plan section on the line 5—5 of Figure 1;

Figure 6 is a fragmentary vertical section 55 on the line 6—6 of Figure 1; and

Figure 7 is a side elevation shown partly in section of a duplex water softening unit to which the apparatus illustrated in Figure 1 is adapted to supply brine and flush water.

In said drawings, 1 is a tank which contains a bed of salt 2 through which water flows downward to dissolve the salt for producing the brine. This brine is used in a system of water softening in which a rapidly regenerating water softening material such as glauconite or other suitable base exchange silicates is used for softening the water. The water softening material is used in the form of a filter bed and as the water to be softened filters through this bed the calcium, magnesium and other salts which are in the water rendering it hard combine with the filtering material. In time the particles of the water softening material take up such quantities of the hardening salts 75 from the water that the softening action gradually ceases. If brine is then forced through the filter bed these hardening salts are replaced by sodium of the brine and carried away and the water softening material is thus regenerated.

In Figure 7 I have shown a filtering unit 3 comprising a pair of suitable tanks which contain a suitable bed of the water softening material and I have provided suitable pipes, 80 valves, and connections to be more fully described hereinafter for delivering both brine and flush water from the apparatus shown in Figure 1 to the water softening unit for regenerating the filter bed and for flushing out the brine used in such regeneration and for washing away the collected salts of calcium, magnesium, etc.

For controlling the flow of brine and flush water to the softening unit 3 I provide a 95 main pipe 4 connected to the water softening unit at one end by the pipe 5, a T 6 connecting the pipes 4 and 5. The pipe 4 extends over the tank 1 and is looped back over the tank, being supported upon cross bars 7 at 100 the top of the tank, which is open. The receiving end 8 of the pipe 4 is connected to a service pipe 9 for fresh water through a three-way valve 10, which is adapted to be manually operated.

I connect the opposite side of the three-way valve 10 to the side opening of the T 6 by a pipe 11. This connection is for the purpose of providing means for drawing the brine out of the brine tank 1 and forcing it 110

to the water softening tanks. This is accomplished by an ejector 12 in the pipe 11 which is connected by a pipe 13 to the bottom of the tank 1. To prevent back flow 5 through the pipe 13 into the tank 1, I provide a check valve 14 in this pipe. A stop valve 15 in the pipe 13 permits the regulation of the flow of the brine to provide the desired strength of solution which is preferably about 5%.

It is sometimes desirable to hasten the flow of the brine to the water softening tanks and for this purpose I provide a steam ejector 16 connected to the pipe 11 beyond the 15 point where the brine is delivered and which forces the solution up into the T 6 and on to the water softening tanks.

It will be understood, of course, that when the three-way valve 10 is set to supply water 20 through the pipe 11 to force brine to the filter beds no flush water is flowing through the pipe 4 and on the other hand when it is set for supplying water through the pipe 4 no water is flowing through the pipe 11.

I provide a salinometer 17 for testing the strength of the delivered brine solution. This is arranged in the upper part of the tank 1 so that the overflow therefrom will run into the tank and it is connected by a 30 pipe 18 to the pipe 11 between the steam ejector 16 and the T 6 which pipe is controlled by a stop valve 19.

For supporting the apparatus above the tank 1, I provide a framework 20 mounted on 35 the cross bars 7. Both the upper and the lower branches of the pipe 4 are secured to this framework.

In the upper branch of the pipe 4, I provide first a stop valve 21, then a check valve 40 22 for preventing back flow through this pipe, then a weighted valve 23 for controlling the flow through the pipe.

At the delivery side of the valve 23, I provide a drain pipe 24 connected to the 45 pipe 4, having an adjustable stop valve 25. This pipe permits delivery of fresh water to the tank 1 to replace that which is drawn off when forcing the brine to the softening unit and by adjusting the valve 25, I can

50 determine the time during which I permit fresh water to flow into the tank 1 through the pipe 4 to replace the liquid withdrawn therefrom and which determines the time during which flush water flows from the regulating apparatus to the softening unit.

In the connection 26 between the upper and lower branches of the pipe 4, I insert a T 55 27. A horizontal pipe 28 connects with the T and has interposed therein a shut-off valve 29 controlled by a lever 30 and weight 31. The valve 29 is closed by gravity and is opened by a float 32 in the tank 1. This float is preferably in the form of a short cylinder 33 of relatively large diameter so as to give a strong lifting force and

terminates at its upper end in a coned top 34 from the center or apex of which projects a guide rod 35. This rod is guided by horizontal guide arms 36 and 37, which project from a fixed rod 38 mounted on the frame 70

20 and to which said arms are secured by set screws 39. The arms are adjustable on the rod 38 to limit the vertical movement of the float. The guide rod 35 has secured thereon 75

between its ends a stop collar 40 which is adapted to rest upon the lower guide arm 36 to support the float when the water level lowers to a point below the float. When the water rises in the tank and the float rises 80 high enough the stop collar 40 engages the valve lever 30 and lifts the same thus opening the valve 29 Fig. 2 and permitting water

85 to flow through the pipe 28 to a T 41 which supplies water to a vertical hydraulic cylinder 42. This cylinder contains a piston on a piston rod 43, which projects from the upper end of the cylinder, and is pivotally connected to a vertically swinging lever 44 pivotally mounted at one end on a fixed pivot 45 carried by the frame 20. De-

pending from the free end 46 of the lever 44 is an operating rod 47 pivotally joined to the lever 44. This rod passes through a bracket 48 carried by a weighted valve lever 49 which controls the opening and closing of 90 said valve 28. The rod 47 has an adjustable stop collar 50 beneath the bracket 48 so that when the water is admitted to the hydraulic cylinder 42 and the rod 47 is lifted the stop 95 50 will engage the bracket 48 on the valve lever 49 and close the valve 28 and will hold it closed as long as the valve 29 is open,

100 thus stopping the flow of flush water to the water softening unit at such time. To release the water from the hydraulic cylinder 42 when the valve 29 closes I provide a drain pipe 51 connected with the T 41 and de-

105 pending into the tank 1. The lower end of this drain pipe is controlled by a float valve 52 adapted to be opened as soon as the water drops below a given maximum level 53 in said tank and to be closed when the water in the tank 1 again rises to said level.

The operation of the mechanism so far 110 described is as follows:—

Presuming that the three way valve 10 has been set to admit water from the service main 9 to the pipe 11, the water flows through said pipe and the pipe 5 to the softening tanks drawing with it the proper percentage of brine from the tank 1. This is allowed to continue until the level of liquid in tank 1 is lowered from high level 53 to low level 54 (see Fig. 1). Then the valve 10 is manually operated to shut off the flow of water to the pipe 11 and supply water to the main supply pipe 4. During the time the water has been flowing through the pipe 11 the level of water in the tank 120

1 has dropped from the upper level 53 to the lower level 54, thus opening the valve 52 and dropping the float 32 to the lower limit of its movement and permitting the valve 29, Fig. 2, to close. The opening of the valve 52 permits the piston in the hydraulic cylinder to drop, thus permitting the main valve 23 to be opened by its weighted lever 49.

10 At the time that the valve 10 is opened to deliver water in the main pipe 4 the main valve 23 is open and water can flow in full volume through the pipe 5 to the water softening unit, this flow of water is for flushing 15 or washing out the brine and the dissolved salts of calcium, magnesium, etc. produced by the flow of brine just previous through the pipe 11. At such time also the valve 29 is closed so that no water flows to the hydraulic cylinder or to the drain valve 52, but water is at this time supplied to the tank 1 through the pipe 24 and adjustable valve 25.

As no liquid is being drawn from tank 1 25 during this interval the water flowing through the supply pipe 24 gradually raises the level therein, the time required for the level to reach the upper water level 53 being regulated by the amount of water permitted 30 to flow through the valve 25.

As the liquid level rises to the upper limit 53 the valve 52 is first closed by its float, and as the float 32 is lifted, it brings the stop 40 into contact with the lever 30 and 35 opens the valve 29 to supply water to the pipe 28. When the valve 52 is closed by the lifting of its lever the water supplied to the pipe 28 through valve 29 operates the piston in the hydraulic cylinder 42 substantially 40 instantaneously shutting off the flow of water through the main pipe 4 to the water softening unit and as the pipe 24 connects with the main pipe 4 beyond the valve 23 the supply to the tank 1 is also 45 thereby stopped.

The valves remain in such condition until the three way valve 10 is again manually operated to cut off the water from the supply pipe 4 and connect it to the pipe 11 for 50 again supplying brine to the water softening unit. As soon as the supply is shut off from the pipe 4 by changing the valve 10 and the water level lowers in the tank 1 sufficient to open the drain valve 52, the 55 hydraulic cylinder 42 is drained and thereby the main valve 23 is opened, the valve 29 is closed, and all is in readiness for another cycle.

To assist in the easy withdrawal of the 60 brine at the bottom of the tank 1 through the pipe 13, I provide a layer of gravel 55 in the bottom of the tank for supporting the salt 2 and through which the brine can settle to the bottom of the tank, leaving 65 any sticks, strings or other non-soluble for-

8
eign materials in the salt on top of the gravel.

I provide a platform 56 for supporting the lower end of the pipe 13 free from the bottom of the tank 1. This platform forms 70 a clean brine reservoir, and consists of a flat top member 57 supported near its edges on suitable supporting members 58 having notches 59 in their lower edges through which the brine can readily flow to the 75 lower end of the pipe 13.

The form of softener unit which I preferably use comprises a pair of tanks 60 cross connected in such a manner that while softened water is being drawn from one of the 80 tanks the softening material in the other tank can be in process of regeneration. This is for the purpose of being able to provide a substantially continuous supply of softened water.

85 Within the upper end of each tank is arranged a system of perforated pipes 61 through which the water to be softened can be supplied from a pipe 62 connected with a water service pipe or other supply of 90 fresh water. The connection between the pipe 62 and the perforated pipes 61 in the two tanks consists of a pipe 63 cross connecting the inlet to the pipes 61 in the two tanks and having a T 64 between its ends 95

to which the supply pipe 62 is connected. Between the T 64 and the tanks are valves 65 for shutting off the flow of water to either tank. The fresh water when supplied to either tank enters the same through the 100 perforated pipes substantially evenly over the whole horizontal area of the tank, flowing down through the softening material therein and escapes through a similar system of perforated pipes 66 at the lower end 105 of the tank. The lower system of perforated pipes are similarly cross connected by a pipe 67 having a T 68 between the same for delivering the softened water to a pipe 69 for leading it to a place of use. Between 110 the T 68 and the tanks the pipe 67 is provided with valves 70 so that softened water can be drawn from either tank as desired and the flow from the other tank shut off.

Between the valves 70 and the tanks, the 115 pipe 67 is provided with a T 71 on each side, which T's are connected with the supply pipe 5 for delivery to the tanks 60 of the brine and flush water as hereinbefore described. The pipe 5 is connected to the 120 two T's 71 by branches 72 which are controlled by stop valves 73 so that the brine and flush water can be sent to either tank desired, while the softened water is being drawn from the other tank.

125 The brine and the flush water entering the tank through the lower system of perforated pipes 66 flows into the tanks substantially uniformly over the whole horizontal area thereof and rises through the 130

softening material in the tank to the upper systems of perforated pipes 61 through which they escape. In similar manner to the lower cross connection 67, the upper 5 cross connection 63 is provided with T's 74 in each branch between the valve 65 and the tanks and these T's are connected to a delivery pipe 75 by branches 76, each of which is controlled by a stop valve 77 so that as 10 fresh water to be softened is flowing down through one tank from a supply 62 to the delivery 69, brine or flush water can be flowing upward through the other tank from the pipe 5 to the waste pipe 75.

15 It will now be clear that if the supply of brine or flush water is started or terminated slowly so that but a small flow of either is maintained for any appreciable length of time such flow will not spread evenly and 20 uniformly over the whole horizontal area of the tank 60 through which it is flowing, but will seek the line of least resistance, naturally finding a path through the softening material almost directly from the inlet at 25 the bottom to the outlet up at the top, thus wasting time, water and salt.

The maximum flow of the brine and the flush water which I am able to maintain throughout the periods of salting and flushing 30 accomplishes the regeneration of the filter beds in a minimum time and without the loss of any salt or flush water.

I claim:

1. The method of regenerating a filter 35 bed for softening water, which consists in causing a maximum flow of brine through the filter bed, then cutting off the flow of brine, then causing a flow of flush water through said bed for a predetermined time 40 and at a substantially maximum flow, and then substantially instantaneously stopping the flow of flush water.

2. The method of regenerating a filter 45 bed of water softening material which consists in maintaining a full flow of brine of predetermined strength through the bed for a desired time, then shutting off the flow of brine, then causing flush water to flow through the filter bed for a predetermined 50 time, the flush water flowing in substantially maximum volume during the whole of said time.

3. The method of regenerating a filter 55 bed of water softening material which consists in maintaining a full flow of substantially five percent brine through the bed for a desired time, then shutting off the flow of brine, then causing flush water to flow through the filter bed for a predetermined 60 time, the flush water flowing in substantially maximum volume during the whole of said time, and at the end of said time instantaneously stopping the flow of flush water.

4. In a mechanism for providing a flow 65 of brine and flush water for regenerating a

filter bed of water softening material, a brine tank, means for providing a supply of fresh water, means for providing a supply of saturated brine, means for drawing brine from the tank and delivering it to 70 said filter bed to be regenerated, means for stopping the flow of brine solution, means for delivering flush water to the filter bed for a predetermined time interval, and for maintaining the flow of flush water at substantially maximum rate during said time 75 interval, means for effecting the substantially instantaneous stoppage of the flow of flush water at the termination of said time interval, and means for adjusting and controlling said time interval.

5. In combination with a water softening system of the kind described, a brine tank, a source of supply of fresh water, means for delivering water from the source of supply 80 to a filter bed of water softening material, means for mixing brine from the brine tank with the fresh water for making a brine of the desired strength, to regenerate said material, means for stopping the flow of brine, means for delivering a constant flow of 85 flush water to the filter bed for a predetermined time interval, a valve for controlling the flow of flush water, a liquid connection to supply fresh water to the brine 90 tank to replace the brine withdrawn, and means for controlling the rate at which the water is delivered from said liquid connection to control said time interval, a bypass connected with the flush water pipe in advance of said valve, a hydraulic cylinder connected with said bypass for controlling said valve, means for draining said bypass to prevent operation of the hydraulic cylinder, and a float valve in the brine tank for 95 closing said drain when the liquid level rises therein to a predetermined point whereby said hydraulic cylinder substantially instantaneously closes said valve.

6. In a system of the kind described, a 100 flush water pipe for delivering flush water to a filter bed of water softening material, a valve for stopping the flow of flush water, a branch pipe connected with the flush water pipe in advance of the valve, hydraulic 105 means for closing said valve connected to said branch pipe, means for draining the branch pipe and preventing the operation of the hydraulic means, means for closing said drain to cause the hydraulic means to 110 substantially instantaneously close said stop valve.

7. In a mechanism for controlling the flow of brine and flush water to a filter bed of water softening material for regenerating same, a brine tank with a brine reservoir for saturated brine substantially at the bottom thereof, a pipe leading from said reservoir to the filter bed, an ejector interposed in the pipe connected to a supply of 115

fresh water and adapted when fresh water is flowing through the pipe to draw brine from the reservoir and deliver it to the filter bed, a flush water pipe also connected to the delivery pipe means for maintaining a flow of fresh water at a maximum rate during a predetermined time interval, means for effecting a substantially instantaneous

stoppage of the flow of flush water at the termination of said time interval, and means for adjusting and controlling said time interval.

Signed at Chicago, Illinois, this 30th day of July, 1920.

FOREST F. AULT.
